United States Patent Office

Des. 230,540
Patented Mar. 5, 1974

230,540

BELT

Henry Gillman, 100 College Ave.,
North Tarrytown, N.Y. 10491

Filed Feb. 6, 1973, Ser. No. 330,007

Term of patent 14 years

Int. Cl. D2—07

U.S. Cl. D2—388

FIG. 1 is a front view of a belt showing my new design the plain links continuing as indicated forming a belt of indeterminate length;

FIG. 2 is a top view thereof; and

FIG. 3 is a back view thereof.

I claim:

The ornamental design for a belt, as shown and described.
